stad, Stockholm, Sweden, a joint-stock com-
pany of Sweden

Application April 7, 1941, Serial No. 387,370
In Germany July 10, 1940

2 Claims. (Cl. 221—118)

This invention relates to a device for distributing portions of pulverous, granular or other material, for instance tobacco, sugar, coffee or tablets, which portions may be packed immediately or delivered to a weighing process, for instance before they are packed.

It is a main object of the invention to provide simple, efficient and rapidly operating means for delivery of material from a receptacle without subjecting the material to rough treatment, thus avoiding grinding or crushing action upon same.

In the drawings:

Fig. 1 is an elevational front view of an embodiment of a distributing machine according to the invention;

Fig. 2 is an elevational sectional view taken on the line II—II of Fig. 1;

Figs. 3 and 4 illustrate two steps of the distributing process;

Fig. 5 shows a part of the machine, and

Fig. 6 is a cross sectional view taken on the line VI—VI of Fig. 5.

It is assumed, by way of example, that the machine shown in the drawings is adapted for distributing portions of tobacco mass which is supplied to a receptacle 2 which has a joining bottom plate 3. At its bottom the receptacle 2 has four openings 50, and in their lower position four measuring chambers 4 form each a downwardly directed extension of said openings. The measuring chambers 4 are secured to a beam 10 which is secured at its ends to two rods 11 which are displaceable up and down in the frame 51. The rods 11 are each by means of a link 15 and a lever 14 moved up and down by a cam disc 13, secured to a rotating driving shaft 12, so that the measuring chambers 4 move periodically between the end positions shown in Figs. 2 and 3. A piston 5 is movable up and down in each measuring chamber 4. The pistons 5 are mounted each on a rod 17, and said rods are jointly secured to a cross bar 18, which is displaceably mounted on the rods 11. The cross bar 18 is operated by a pair of links 19 and levers 20 secured to a shaft 1, which is rotatably journalled in the machine frame 51. Another lever 21, secured to the shaft 1, is operated by a cam disc 22 which is secured to the shaft 12. The rods 17 are adjustable relative to the rods 11 in such manner that the pistons 5 can be adjusted vertically relative to the measuring chambers 4, whereby the size of the tobacco portions can be changed at desire. For that purpose abutments 23 resting on standards 48 are adjustably mount-

ed on the rods 11, viz. by means of two pinions 46 (Figs. 5 and 6) on a shaft 24; said pinions mesh with toothed parts 41 of the rods 11. For adjustment the shaft 24 is turned, so that the abutments 23 are moved simultaneously up and down on the rods 11, whereafter the abutments are clamped to the rods 11 by means of set screws 42.

In operation, the measuring chambers 4 and the pistons 5 are first elevated into the position shown in Fig. 3 with their upper rims at a level with a plate 6, whereby each measuring chamber 4 separates from the contents of the receptacle 2 the tobacco portion slipped down into it from the receptacle 2. Thereby an excess of tobacco (see Fig. 3) is separated, which has to be removed, so as to obtain a portion of an exactly predetermined size. For that purpose a scraping-off plate 7 is movable to the left (Fig. 3) close over the upper rim of the measuring chamber 4 and scrapes off the excess, which is thereby again supplied to the tobacco mass in the receptacle 2. Immediately thereafter the piston 5 is elevated, whereat the measuring chamber remains in its height shown in Fig. 4, so that the tobacco portion is pushed out of same. Immediately thereafter the scraping-off plate 7 moves to the right (Fig. 4), so that the tobacco portion is displaced upon the plate 6 and slips from the plate 6 down through the channel 8 into the funnel 9, from which it is supplied to the treatment, for instance manufacture of cigars.

For advancing and reversing the scraping-off plate 7 as mentioned there is provided a third cam disc 29 mounted on the shaft 12 and operating a lever 28, which is secured to a rock shaft 27. Furthermore, two lever arms 26 are secured to the shaft 27, and their ends are secured to a rod 25 which is movable in guide slots 54. The plate 7 is secured to said rod 25.

In case material likely to be crushed is manipulated it is advisable to provide the plate 7 at its bottom end with a scraping-off brush or the like, or to replace it completely by such a brush.

I claim:

1. In a device for distributing portions of pulverous, granular, fibrous or other material, for instance tobacco, a receptacle for the material to be distributed, a measuring chamber having an open top end and being movable up and down in said receptacle, a piston movable up and down within said chamber, a table, a scraping-off member, and means to first elevate said chamber to position its top end substantially at a level with said table, then to move said scraping-off

member across said top end to remove material projecting out of said top end, then to elevate said piston within said chamber to expel from said chamber onto said table a portion of material separated from the contents of said receptacle by the measuring chamber when being elevated, and thereafter to reverse said scraping-off member to move again across the top end of said chamber and table to transfer material therefrom to a receiver.

2. In a device for distributing portions of pulv-
erous, granular, fibrous or other material, for
instance tobacco, a receptacle for the material to
be distributed, a measuring chamber having an
open top end and being movable up and down in
said receptacle, a piston movable up and down

5 within said chamber, a receiver positioned inter-
ally of said chamber, a scraping-off member, and
means to first elevate said chamber to project
above the material in said receptacle, then to
move said scraping-off member across said top
end in a direction from said receiver to remove
10 material projecting out of said top end, then to
elevate said piston within said chamber to ex-
pel from said chamber a portion of material sepa-
rated from the contents of said receptacle by
the measuring chamber when being elevated, and
thereafter to reverse said scraping-off member to
move again across the top end of said chamber to
transfer material therefrom to said receiver.
